UNITED STATES PATENT OFFICE.

GEORGE H. WRIGHT, OF BUFFALO, NEW YORK.

DESIGN FOR A NURSING-BOTTLE.

SPECIFICATION forming part of Design No. 30,007, dated January 17, 1899.

Application filed December 23, 1898. Serial No. 700,175. Term of patent 14 years.

To all whom it may concern:

Be it known that I, GEORGE H. WRIGHT, residing in Buffalo, county of Erie, and State of New York, have invented and produced 5 a new and original Design for Nursing-Bottles, of which the following is a specification, reference being had to the accompanying drawings, forming part thereof.

Figure 1 is a side view of the bottle complete. Fig. 2 is an edge view thereof.

As shown in the accompanying drawings, the leading or material feature of my design consists in a nursing-bottle having a somewhat elliptical body terminating abruptly at 15 the bottom, the periphery of said bottom being headed, and the upper end terminating in a short contracted neck, said neck being provided with a bead, the whole producing a unique and unitary article of manufacture.

a is the body.

b is the bottom, and *c* are the beads or threads surrounding the bottom.

d is the neck, and *e* is the bead surrounding the upper end of the neck.

It will be evident that the body of the bottle may be engraved or molded with configurations of any ornamental design desired.

Having described my design, what I claim, and desire to secure by design Letters Patent, is—

The design for a nursing-bottle, as herein described and shown.

In witness whereof I have hereunto set my hand this 17th day of December, 1898.

GEORGE H. WRIGHT.

Witnesses:

ALBERT NOWAK,
W. E. NOWAK.
